CLAIM

The ornamental design for a star-shaped shade for a lighting fixture, as shown and described.

DESCRIPTION

FIG. 1 is a perspective view of a star-shaped shade for a lighting fixture adapted to be mounted on a support surface in accordance with a first embodiment of the present invention;

FIG. 2 is a front elevational view of the star-shaped shade for a lighting fixture illustrated in FIG. 1;

FIG. 3 is a side elevational view of the star-shaped shade for a lighting fixture illustrated in FIGS. 1 and 2;

FIG. 4 is a top plan view of the star-shaped shade for a lighting fixture illustrated in FIGS. 1–3;

FIG. 5 is a perspective view of a star-shaped shade for a lighting fixture adapted to be mounted on a support surface in accordance with a second embodiment of the present invention;

FIG. 6 is a front elevational view of the star-shaped shade for a lighting fixture illustrated in FIG. 5;

FIG. 7 is a side elevational view of the star-shaped shade for a lighting fixture illustrated in FIGS. 5 and 6;

FIG. 8 is a top plan view of the star-shaped shade for a lighting fixture illustrated in FIGS. 5–7;

FIG. 9 is a perspective view of a star-shaped shade for a lighting fixture adapted to be mounted to a support surface in accordance with a third embodiment of the present invention;

FIG. 10 is a front elevational view of the star-shaped shade for a lighting fixture illustrated in FIG. 9;

FIG. 11 is a side elevational view of the star-shaped shade for a lighting fixture illustrated in FIGS. 9 and 10;

FIG. 12 is a top plan view of the star-shaped shade for a lighting fixture illustrated in FIGS. 9–11; and,

FIG. 13 is another top plan view of a star-shaped shade for a lighting fixture adapted to be mounted to a support surface in accordance with the third embodiment.

The broken lines are shown for illustrative purposes only and form no part of the claimed design. The orientation of the star-shaped shade for a lighting fixture also forms no part of the claimed design.
